UNITED STATES PATENT OFFICE.

JOHN M. HULL, OF ATCHISON, KANSAS.

ACETYLENE-GAS GENERATOR.

SPECIFICATION forming part of Letters Patent No. 633,844, dated September 26, 1899.

Application filed February 20, 1899. Serial No. 706,129. (No model.)

To all whom it may concern:

Be it known that I, JOHN M. HULL, a citizen of the United States, residing at Atchison, in the county of Atchison and State of Kansas, have invented certain new and useful Improvements in Acetylene-Gas Generators, of which the following is a specification.

My invention relates to gas-generators, and more particularly to that class of combined automatic generators and holders employed in the manufacture of acetylene gas, and the object is to provide a simple, safe, effective, and reliable device of this character.

To this end the invention consists in the construction, combination, and arrangement of the same, as will be hereinafter more fully described, and particularly pointed out in the claims.

In the accompanying drawings the same reference characters indicate the same parts of the machine.

Figure 1 is a vertical section of my improved acetylene-gas generator. Fig. 2 is a detail view of the carbid-drum-actuating mechanism. Fig. 3 is a similar view of the pocket-tripping mechanism for the carbid-drum. Fig. 4 is a sectional detail of the gasket-seal between the inner and outer generator-drums, the lower end of the inner drum or bell forming the usual water seal in the outer drum, as shown in Fig. 1. Fig. 5 is an enlarged detail section of the generator. Figs. 6 and 7 are detail views.

C denotes the generator-tank, which is supported by the adjustable leg I and connected to the gas-holder tank A by the brace B⁶ and the communicating gas-pipe G.

The generator-tank C is provided with a funnel or spout E, the lower end of which opens into said tank through the orifice e, closed by an inwardly-opening flap-valve e'.

C' denotes a gate-valve for removing the undissolved carbid, and C⁸ a plug-cock for removing the spent carbid from the generator.

C' denotes the removable bell, open at the bottom and closed at the top by the cover C¹¹, which forms an air-tight joint with the generator-tank by means of the rubber gasket C⁹, seated on the annular lip or shoulder C¹⁰, formed on the tank C, the parts being held together by the clips C¹¹. A water seal is also formed between the bell and tank by the wa-

ter in the latter. This gasket-packing C⁹ acts as a check to prevent the water from rising over the top of the tank C in case of unusual pressure, as would be the case when carbid-dust is used. The bottom face of this cover is convex in form, as shown, so that the water of condensation or moisture will be conducted to the center, and thus returned to the water in the tank without coming in contact with the calcic carbid in the pockets in the carbid-chamber.

F denotes a horizontal water-tank fixed in the generator-bell and formed with an inlet 65 for filling and a vertical passage-way F³, in which are fixed the deflector-plates F'.

H denotes a vertical pipe, its upper open end being rigidly fixed in the top C¹² by the lock-nuts, as shown.

H' denotes an encompassing pipe or sleeve, the upper end of which terminates below the cover and to which the carbid-chamber is fixed. The lower end of the sleeve H' is provided with a water-inlet orifice H¹⁰, and its immediate end carries an internal collar H¹, to which a vertical pipe H² is fixed and its upper end extends beyond the pipe H to receive the inverted-crown ratchet-wheel H³, so that when the ratchet-wheel H³ is rotated a corresponding movement will be imparted to the carbid-chamber, and, as there is a water-space between the pipes H, H', and H², a perfect water seal is formed between the inside and outside of the generator without the use of stuffing-boxes, and thereby permitting the carbid-chamber to be operated in a simple and effective manner.

C^a denotes the horizontal carbid-chamber fixed to the upper end of the sleeve H', and it is divided into a series of radiating segmental pockets C², open at the top, each provided with a hinged bottom C³.

C⁴ denotes a vertical trip-rod journaled on the outside of the chamber C^a, and its lower 95 end is provided with a lateral horizontal toe c, which normally extends under the hinged bottom to retain it in place, and the upper end of said rod terminates in a correspondingly-formed trigger c², which travels around the inner face of a concentric flange C⁵ (fixed to the cover C²) and which holds the toe in position under the hinged bottom C³. The forward end of this flange C⁵ flares outwardly,

so as to extend across the path of the trigger C^2 to engage it and force it inwardly, thereby turning the trip-rod on its axis and turning the toe c under the bottom to hold it in place.

5 This flange is broken away to release the trigger for a space corresponding to the width of the passage-way F^8 in the condenser drum or tank F, and immediately above said passage-way there is formed in the cover C^{12} a hand-hole covered by a removable gasket-packed plate D, from the lower face of which a dog D' projects, the outer beveled face of which projects into the path of the trigger c^2 , so as to divert it to one side and turn the toe c from 15 under the hinged bottom C^3 and permit it to discharge its contents into the water contained in the tank C. The condenser-drum F is filled with cold water, and as the gas rises from the water in the generator-tank it 20 comes in contact with this cold tank, which cools the gas and causes it to part with its water of condensation, which accumulates on the drum and drips back into the tank C.

C^6 denotes an inclined lug fixed on top of 25 the water-chamber F and in the path of the open hinged bottom, so that the latter will ride over said lug and close the bottom, after which the trigger c^2 comes in contact with the flange C^5 , fixed to the cover C^{12} , concentric to 30 the axis of the tank C, which turns the trip-rod c^4 on its axis and draws the toe c under the bottom C^3 to support it in place.

H^3 denotes a rod journaled in the pipe H^2 , and its lower end carries the horizontal blades 35 H^4 , which serve to agitate the carbid in the bottom of the tank C, and the upper end of said rod carries a crank-wheel H^6 , by means of which the rod and agitator are manipulated.

40 It will be noted that the water in the generator-tank rises in the pipe H^2 and surrounds the rod H^3 to the same level as the water in the tank and in the pipes H and H' and forming a perfect water seal against the escape of 45 gas without the use of stuffing-boxes.

H^6 denotes a weighted pawl pivoted on the lever H^7 , swiveled on the vertical stud H^{12} , fixed in the top C^{12} , the free end of the pawl engaging the teeth on the ratchet-wheel H^5 , 50 and the free end of the lever carries a friction-roller H^8 , which extends between the parallel arms of the U-shaped rod B^5 , fixed to a bracket B^4 , carried by the gas-holder B, which has a vertical movement in the tank A.

55 The teeth are formed on the bottom face of the ratchet-wheel H^5 , and the toe of the pawl H^6 is held in contact with said teeth by reason of its opposite end being weighted. Consequently as the pawl moves forward it carries the ratchet-wheel with it, and as the pawl moves backward its toe slides over and drops into a tooth at the rearward limit of its stroke.

60 H^{11} denotes a vertical bar having its lower end fulcrumed in a bracket H^9 on the outside 65 of the generator-tank, and its upper end encompasses the outer end of the lever H^7 to

support and prevent it coming into frictional contact with the top or cover of the generator.

The U-shaped rod B^5 is formed with an offset B^7 , which imparts an oscillating movement to the lever H^7 and through the medium of said pawl and ratchet-wheel causes it to rotate the carbid-chamber.

B' denotes a guide-sleeve extending downward from the top of the holder, and its lower end is connected to the corresponding lower edge of the holder by the stay-braces B^8 .

A^5 denotes an axial guide-rod fixed to the bottom J^2 of the tank A for the sleeve B' to slide on, and thereby maintain the holder concentric within the tank.

J denotes a diaphragm or false bottom fixed in the tank A, and A^6 denotes a vertical pipe extending through the bottom J and terminating at a point corresponding to the pre-determined water-level in said tank A.

J' denotes a second diaphragm or false bottom fixed in the tank A below that first mentioned, and in it is fixed an overflow-pipe A^7 , open at both ends, and A^4 denotes the out or supply pipe, the vertical portion of which extends from the lower compartment A^2 through the bottom J' , the compartment A' , the bottom J , and opens into the tank A above the water-level, as shown. This pipe is provided with a lateral branch pipe which extends through the outside of the tank A and connects with the service-pipe leading to the burners.

A^8 denotes the relief or escape pipe, leading from the chamber A^2 , and its upper end has a telescopic engagement with the hooded pipe B^2 , fixed in and traveling with the holder B.

It will be seen that the lower end of the vertical pipe A^4 forms a water seal in the tank, and consequently any unusual pressure of gas in the gas-holder will pass out through the lower end of the said pipe A^4 and escape into the tank A^2 , and thence through the relief-pipe A^8 into the atmosphere, thus providing a pressure safety-valve in addition to the telescopic safety-relief-pipe A^3 .

An additional advantage in the lower open ends of the pipes A^8 and A^4 is the fact that they provide a discharge-outlet for any condensation that may take place within, and thus do away with the necessity of outside drip chambers or cocks for this purpose.

G' denotes a downwardly curved elbow which serves to conduct the gas from the generator-pipe G below the water-level in the chamber A' , and A^9 denotes a foraminous hood which encompasses said elbow and acts as a scrubber or washer for the gas by separating or dividing it under the water in the chamber A.

A^8 denotes an overflow-funnel fixed to the outside of the tank A and communicating with the chamber A^2 by means of the orifice a , and it serves as a gage to determine the proper height of the water-level in the tank A and chambers A' and A^2 , as will be hereinafter more fully explained.

The manner of operating the machine is as follows: The tank A is filled with water until it reaches the top of the overflow-pipe A⁶. The water then passes down through said pipe into the chamber A' until it reaches the level of the overflow-pipe A⁷, through which it passes downward into the chamber A² until it rises to the level of the mouth of the funnel A⁸, and all three of the tanks A, A', and A² will now be filled to their proper water-level, with the holder B sunk to the level of the water in the tank A, so as to exclude the atmospheric air. The generator-tank C is now filled with water through the funnel E until the proper level is reached, which is ascertained by the water appearing in the bottom of the funnel. Remove the cover D and fill the water chamber or drum F through one of the pockets in the carbid-chambers. Now fill the carbid-pockets one at a time until all are filled. Replace the cover D, and by means of the ratchet-wheel H⁵ turn the carbid-chamber forward until one of the trip-roads comes in contact with the arm D' to trip the bottom C³ of one of the pockets and discharge its contents into the water in the tank C, when the generation of the acetylene gas immediately takes place. The gas now passes through the outlet-pipe G, displacing the wa- ter in the lower end of said pipe G, when it connects with the tank A and escaping through the submerged strainer A⁹ into the space between the water-level and the dia- phragm J in the chamber A', and thence up- ward through the pipe A⁶ into the gas-holder B, causing it to rise and carry with it the rod B⁵. The diagonal offset B⁷, coacting with the antifriction-roller on the outer end of the lever H⁷, throws the pawl H⁶ into position to engage one of the teeth on the ratchet-wheel H⁵. The gas in the holder passes out through the pipe A⁴ to the service-pipes, and as the holder falls, due to the consumption of the gas, the rod B⁵ moves the lever H⁷ in the op- posite direction, thereby rotating the carbid- chamber so as to present a pocket over the passage-way F⁸, and, as hereinbefore de- scribed, the bottom is tripped and the charge of carbid dropped in the water in the gen-

erator-tank to produce a fresh supply of gas, 50 which causes the holder to rise with a like result as before, and this operation is automatically repeated until all of the pockets in the carbid-chamber are emptied of their contents. 55

In the accompanying drawings I have shown my invention in the best form now known to me; but changes in the details may be made without departing from the spirit of my in- vention as set forth in the claims. 60

What I claim is—

1. The combination in a generator of the class described, of the generator-tank C, the removable bell C', the removable cover D, the dog D' fixed thereto and the mutilated flange C⁵ fixed to the bell-cover, the horizontally-rotating carbid-chamber C² formed with a series of pockets C³ a hinged bottom mounted beneath each pocket, trip-rods C⁴ carried by the carbid-chamber and adapted to sup- 70 port the hinged bottoms in a closed position, and arranged to coact with said dog D' to re- lease said bottom at a predetermined point, substantially as and for the purpose set forth.

2. In a generator of the class described, the combination with the tank C, of the bell C' and its cover C¹², the duplex pipes H and H' provided with the orifice H¹⁰, the rod H⁸ and the blades H⁴ fixed to the lower end of said rod, substantially as and for the purpose set 80 forth.

3. In a generator of the class described, the combination with the tank C the bell C' the duplex pipes H and H', the horizontally-rotat- 85 ing carbid-chamber and the ratchet-wheel carried by the said pipes, the pawl and lever coacting with said ratchet-wheel, of the tank A and holder B, and the U-shaped rod B⁵, co- acting with said lever to rotate said ratchet- wheel, substantially as and for the purpose 90 set forth.

In testimony whereof I affix my signature in presence of two witnesses.

JOHN M. HULL.
